UNITED STATES PATENT OFFICE.

WILLIAM E. ZIERDEN, OF JOHNSONBURG, PENNSYLVANIA.

DIAPHRAGM.

1,180,220.

Specification of Letters Patent. Patented Apr. 18, 1916.

Application filed August 9, 1915. Serial No. 44,635.

To all whom it may concern:

Be it known that I, WILLIAM E. ZIERDEN, a citizen of the United States, residing at Johnsonburg, in the county of Elk and State of Pennsylvania, have invented certain new and useful Improvements in Diaphragms; and I do hereby declare the following to be a full, clear, and exact description of the invention, such as will enable others skilled in the art to which it appertains to make and use the same.

This invention relates to diaphragms for use in conjunction with fluid under pressure for regulating and similar purposes, and has for an object to provide a diaphragm presenting the requisite flexibility but embodying means to prevent crystallization and fracturing under the usual contingencies of operation.

In the use of expandable diaphragms for fluid pressure regulation it has been demonstrated that after being used some time the material of the diaphragm becomes crystallized, especially adjacent the periphery, and fractures by reason of such crystallization.

The object of the present invention is to produce a diaphragm composed of material increasing in thickness toward its periphery, possessing the necessary flexibility by reason of the thinness of the material adjacent the center whereby both flexibility and resistance to crystallization and fracture are provided.

With these and other objects in view the invention consists in certain novel features of construction, combination and arrangement of parts as will be hereinafter more fully described and claimed.

The drawing shows a number of the diaphragms connected together in ordinary working order, part being shown in diametrical section, and others in edge elevation.

The drawing as above noted shows a plurality of the diaphragms connected each with the other, but it is to be understood that while this is a customary manner of employing these diaphragms the invention resides in a single diaphragm only, or in merely one side of a diaphragm as shown, irrespective of the manner in which it may be connected to any adjacent diaphragms or other bodies.

As shown in the drawings, the diaphragm plate 10 is produced of any desired shape 55 but preferably, though not necessarily, circular, and also preferably though not necessarily having a central opening 11 into which a nipple 12 is inserted from the inside, having an enlarged head 13 bearing 60 against the inner surface of the plate 10 and with a collar 14 screwed down upon the nipple upon the exterior of the plate 10 to produce a fluid-tight joint, solder or other ordinary attaching means being used 65 when found desirable. It will be noted that the thickness of the plate 10 increases from the center to an annular rib 15 at the periphery. When used in conjunction with another similar plate to form a complete 70 diaphragm expandible on both sides, the equivalent plate 16 is secured to the plate 10 at the periphery in any approved manner as by the use of the rivets 17, also supplemented by solder if found desirable. Before the two plates 10 and 16 are put together the plate 16 is provided with a nipple 18 having a head 19 upon the inner surface of the plate 16, the exterior threaded surface of the nipple 18 being of the proper 80 size to screw into the internally threaded nipple 12, the collars 14 may also serve as spacers between the several pairs of plates if desired. One of the enlarged heads as 13 or 19, here shown as the head 19, is 85 provided with a plurality of radial grooves 20 which serve to admit the fluid from the central openings of the stack of nipples 18 to the chamber interlying the plates 10 and 16 so that communication is always open 90 between the central passage for the fluid and the space between the diaphragm plates even when the plates are contracted to closed position as shown in the drawing.

It is obvious that under certain conditions 95 the extreme plate need not be provided with a central opening as indicated at 21, the plate being entirely imperforate and bearing against any conveniently disposed body as 22 which may be stationary or movable 100 as circumstances may make necessary or desirable.

It will be understood that the invention resides in one only of the plates 10 or 16 irrespective of the manner in which it is 105 connected to other plates or other bodies,

such connection or use covering the entire field of utility for such expandible diaphragms.

What is claimed is:—

- 5 1. In a device of the class described, a plurality of plates spaced apart and each provided with a central opening, said plates increasing in thickness uniformly from the opening to a point distant therefrom and 10 being connected near their outer edges, a threaded nipple having a flanged head passing through the opening of each plate, the nipples being reversely arranged with their heads adjacent to each other.
- 5 2. In a device of the class described, a plurality of plates spaced apart and each provided with a central opening, said plates increasing in thickness uniformly from the opening to a point distant therefrom and 20 being connected near their outer edges, a threaded nipple having a flanged head passing through the opening of each plate, the nipples being reversely arranged with their

heads adjacent to each other, and one of the nipples having an internal bore larger than 25 the other for receiving a nipple connected with an adjacent plate.

3. As an article of manufacture, a diaphragm for a pressure regulating device, comprising a flat sheet of metal having a 30 central opening and increasing in thickness from the edges of the opening toward the periphery.

4. As an article of manufacture, a diaphragm for a pressure regulating device, 35 comprising a flat sheet of metal having an opening, and an annular rib adjacent to the outer edge, said plate increasing in thickness from the opening to the rib.

In testimony whereof I affix my signature 40 in presence of two witnesses.

WILLIAM E. ZIERDEN.
